UNITED STATES PATENT OFFICE.

TUNIS L. COLLINS, OF BERWYN, ILLINOIS, ASSIGNOR TO THE ANGLO-AMERICAN KEY COMPANY, LIMITED, OF CHICAGO, ILLINOIS.

DESIGN FOR A KEY FOR KEY-OPENING CANS.

SPECIFICATION forming part of Design No. 32,579, dated April 24, 1900.

Application filed March 3, 1900. Serial No. 7,249. Term of patent 14 years.

To all whom it may concern:

Be it known that I, TUNIS L. COLLINS, a citizen of the United States, residing at Berwyn, in the county of Cook and State of Illinois, have invented and produced a new and original Design for Keys for Key-Opening Cans, of which the following is a specification, reference being had to the accompanying drawings, forming a part thereof.

10 In the drawings, Figure 1 is a plan view of a key embodying my novel design. Fig. 2 is a side elevation of the same.

The main features of my novel design are as follows: The key consists generally of a 15 cylindric metal rod or wire bent at one end in looped form to constitute a handle, which, projecting laterally on each side of the straight part of the rod, forms the shank. The said shank, near its end opposite from said handle, 20 is split or divided longitudinally on a plane passing through the central axis of the

shank and parallel with the plane of the handle. The two parts on each side of said split are deflected outwardly away from each other and are separated, so as to form a slot the 25 sides of which are parallel, except at the ends thereof, where the end portions of the separated parts join the body of the shank by reversed curves.

Having described my novel design, what I 30 claim as new, and desire to secure by Letters Patent, is—

The design for a key for key-opening cans, as herein shown and described.

In testimony whereof I have signed my 35 name to this specification, in the presence of two witnesses, this 9th day of February, A. D. 1900.

TUNIS L. COLLINS.

In presence of—

GERTRUDE BRYCE,
DOROTHY E. MARMON.
